PORTABLE SHOE SHINE BOX

Malcolm E. Cooper, Dorset, Vt., assignor to The Kiwi Polish Company Proprietary Limited, Melbourne, Victoria, Australia, a corporation of Australia

Application February 11, 1958, Serial No. 49,597

Term of patent 7 years

(Cl. D9—2)

The figure is a perspective view of a portable shoe shine box, showing my new design.

The side and end of the article not shown are substantially the same in appearance as the respective side and end shown.

I claim:

The ornamental design for a portable shoe shine box, as shown and described.
